REFRIGERATING APPARATUS

Harry B. Hull, Dayton, Ohio, assignor to General
Motors Corporation, Dayton, Ohio, a corpora-
tion of Delaware

Application November 30, 1934, Serial No. 755,383

26 Claims. (Cl. 62—116)

This invention relates to refrigeration.

It is an object of this invention to provide a simplified refrigerator in which foods may be stored without undue dehydration.

5 Further objects and advantages of the present invention will be apparent from the following description, reference being had to the accompanying drawings, wherein a preferred form of the present invention is clearly shown.

10 In the drawings:

Fig. 1 is a vertical cross-sectional view of an apparatus embodying features of my invention;

Fig. 2 is a vertical cross-sectional view taken transversely of Fig. 1;

15 Fig. 3 is a view similar to Fig. 1, showing a modified form of the invention;

Fig. 4 shows a modification of the embodiment shown in Fig. 3;

Fig. 5 is a view, partly in cross-section and 20 partly in elevation, showing another modification;

Fig. 6 is a view, somewhat similar to Fig. 5, but showing a further modification; and

25 Figs. 7, 8 and 9 are cross-sectional views showing pans adaptable to the modifications shown in Figs. 3 and 4.

In practicing this invention, a cabinet 10 is provided with a food storage compartment 11 which is provided with a cooling unit 12. Preferably, in the modification shown in Figs. 1 and 2, this 30 cooling unit 12 is placed in the upper part of the compartment, and a flat baffle 13 is horizontally extended beneath the cooling unit and curves into a vertical portion 14 to form a vertical flat flue at the rear of the compartment 11. A 35 door 15 is provided at the front of the compartment.

Means are provided for circulating water in contact with the air in the compartment 11. To this end, an air moistener 16 is placed behind the 40 baffle 14 and a drain pan 17 is positioned to catch any unevaporated moisture at the bottom of the vertical flue 18. A pump 19 is connected with the drain pan 17 and with the moistener 16 to form a fluid circulating circuit. A purifier 20 is 45 placed in this circuit and is provided with a purifying medium 21, such as activated charcoal, so that purified water is discharged at the moistener 16. The pump 19 may be driven by an electric motor energized from leads 45.

50 Refrigeration for the cooling unit 12 may be provided by any suitable means. Thus the cooling unit 12 may contain an evaporating space (not shown) within its walls which forms a part 55 of a refrigerating circuit. This circuit may in-

clude a refrigerant liquefying unit 22 from which liquid refrigerant flows through the pipes 23 and 24 to the unit 12 and from whence evaporated refrigerant flows through the line 25 back to the unit 22.

If desired, the cabinet may be provided with a freezing compartment 26 having a cooling unit or evaporator 27 which may also be connected with the refrigerant liquefying unit 22. In such a case and 28 to the evaporator 27 and the evaporated refrigerant may flow through the pipes 23 10 and 28 to the evaporator 27 and the evaporated refrigerant may return through the branch 29 to the suction line 25 and from thence to the unit 22.

It is sometimes desirable to maintain the unit 12 at a higher temperature than the unit 27 and this may be accomplished by providing a pressure regulating valve 30 which is responsive to the pressures in the unit 12 and which throttles the line 25 and prevents the pressure in the unit 12 15 from being reduced below a predetermined limit. This limit preferably is such that the temperature of the unit 12 is maintained high enough to prevent the formation of frost thereon but is cold enough to provide proper refrigeration for the compartment 11. The liquid refrigerant is expanded by a valve 31 which is controlled by a thermostat bulb 32 in such a manner that liquid refrigerant is introduced into the evaporator space when pressure therein is reduced below 20 a predetermined limit, but the valve is throttled by the bulb 32 whenever the refrigerating effect reaches said bulb. A valve 33 is provided for the unit 27 which also may have a thermostatic bulb 34 and which operates substantially in the same 25 manner as valve 31, but is calibrated to lower temperatures.

The refrigerant liquefying unit 22 may include a compressor 35 driven by a motor 36. A compressor discharges into a condenser 37 having a liquid refrigerant receiver 38 which is connected to the pipe 23. An automatic control for starting and stopping the unit 22 is provided, and this may include a bellows 39 which operates the snap switch 40 which starts and stops the motor 36 in response to pressures in the line 25.

40 Means may be provided for evaporating excess moisture. This may take the form of a heater 41 which is connected by an overflow pipe 42 with a drain pan 43. The moisture evaporator 41 may include plates 43 and 44 which are connected to the electric leads 45. When water flows into the evaporator 41, an electric circuit is made between the plates 43 and 44, and the heat thus generated 45

evaporates the water which is then discharged through openings 46 into the atmosphere outside the compartment 11. When the moisture has been evaporated, the electric circuit is opened 5 since the flow of current from one plate to the other is stopped by the absence of a conducting medium between the plates. If desired, a suitable conducting salt may be placed in the evaporator 41 which is dissolved by the condensed moisture 10 and aids in the flow of current from one plate to the other.

Suitable shelves 47 may be placed in the food compartment 11. Also fins 48 may be provided on the cooling unit 12 to enhance the cooling effect 15 of said unit. The fins may be parallel vertical fins on the lower part of the unit 12.

In the operation of the device shown in Figs. 1 and 2, air in the compartment 11 flows around the upper edge of the baffle 13 and is cooled by 20 the unit 12. As this unit is not cold enough to become frosted, moisture may be condensed from the air and the condensate may drip from the fins 48 to the upper part of the baffle 13 from whence it flows to the drain pan 17. The cooled 25 air comes in contact with the moistener 16, which humidifies the air. The moisture 16 may take the form of a downwardly directed spray which follows the air vertical passageway 18. The moistened air is discharged into the main body 30 of the compartment 11 to flow again upwardly over the upper edge of the baffle 14.

In the modification shown in Fig. 3, a cabinet 100 is provided with a food storage compartment 101. A cooling unit is provided for the compartment 101, and this unit may take the form of an evaporator having a freezing section 102 and an air cooling section 103. These sections may be made of metal sheets suitably welded together and bent in the form of nested U's. Refrigerant 40 from the refrigerant liquefying unit 104 flows through the line 105, through the automatic expansion valve 106, to the freezing section 102. From thence it passes through the pipe or passageway 107 to the section 103 and returns 45 through the line 108 to the unit 104. Automatic means for controlling the operation of the unit 104 may be provided. In this case a thermostatic bulb 109 may be placed near the outlet of the cooling unit and may control the bellows 110 50 which actuates a snap switch 111 which controls the starting and stopping of the motor 112. The liquefying unit 104 may include, in addition to the motor 112, a compressor 113, a condenser 114, and a liquid refrigerant receiver 115. Suitable 55 ice trays 116 may be placed in section 102.

Means for moistening the air in the compartment 101 may be provided. This may take the form of a drain pan 117 which may be provided with means for purifying the water and for bringing it in evaporative contact with the air in the compartment 101. Thus a cake 118 of some purifying material, such as activated charcoal, may be supported on the edge of the pan 117. The pan itself may be made of porous material 60 so that the water in the pan may seep through and be evaporated from the outer surface of the pan 117.

The pan may receive water partly or wholly from the cooling unit and partly or wholly from 70 a reservoir 119. The air cooling section 103 preferably is operated on an automatic defrosting cycle such that its surface automatically defrosts at every cycle caused by the starting and stopping of the motor 112. The moisture dripping 75 from the section 103 comes in contact with the

purifier 118 and eventually is evaporated from the outer surface of the pan 117. The reservoir 119 may supply any deficiencies in moisture in the compartment 101. The reservoir 119 may take the form of an inverted bottle resting in the cup 120 which is connected by the pipe 121 with the pan 117 and this maintains a minimum level in the pan 117.

The modifications shown in Figs. 7, 8 and 9 show various types of pans which may be used in the modifications of Fig. 3 and of Fig. 4. In Fig. 7 the pan 117 is substantially as shown in Figs. 3 and 4 and merely shows an enlarged view of the pan and the bracket 122 which supports the purifier 118 from the edge of the pan. In Fig. 8, the pan 117a may be non-porous, in which case a capillary member such as a wick 123 may be moistened by the liquid in the pan 117 and may evaporate the moisture from its un-submerged edge. The pan 117a may be provided with a purifier as shown in Figs. 7 and 9. In Fig. 9 a drain pan 117b may be provided with a purifier 118b which in this case merely rests on the bottom of the pan.

In the modification shown in Fig. 4, a cabinet 125 may be provided with a food compartment 126. A refrigerant liquefying unit 127 provides liquid refrigerant through the line 128 to the cooling unit or evaporator and from whence evaporated refrigerant returns through the line 129 to the unit 127. The cooling unit or evaporator may include the freezing section 130 and the air cooling section 131. The line 128 may divide into lines 132, 133 which supply respectively the freezing section and the air cooling section of the evaporator. An expansion valve 134 controls the flow of refrigerant into the freezing section 131, and this valve may be of the same type as shown at 31, and may be controlled by the thermostatic bulb 135 at the outlet of the freezing section. The air cooling section may have its inlet provided with the valve 136 similar to valve 31 controlled by thermostatic bulb 137 placed at the outlet of the section 131. A constant pressure valve 138 may be placed in the suction line 139 of the air cooling section. Valve 138 is adapted to maintain a refrigerant pressure in the section 131 such that no frost collects thereon, but at the same time the temperature is maintained sufficiently low to cool the compartment 126. The suction line 129 connected to the suction line 139 and to the branch 140 is connected to the freezing section 131. A pan 141 may be provided which may be similar to the pan 117, 117a or 117b. This pan may also be provided with a reservoir 142 similar to the reservoir 119 together with its cup and connection. The motor 143 may be controlled by the snap switch 144 operated by a bellows 145 in response to pressures within the line 129. The unit 127 may also include a compressor 146, condenser 147 and liquid refrigerant receiver 148.

In the modification shown in Fig. 5, a cabinet 150 is provided with a storage compartment 151. A cooling unit may be provided which includes a freezing section 152 and an air cooling section 153. A refrigerant liquefying unit 154, similar to the unit 104 may be provided so that liquid refrigerant flows through the pipe 155 to the expansion valve 156. Expanded refrigerant flows 70 around a hollow sleeve or like construction surrounding the trays 157 and from thence flows into the internal space of the hollow plate 153. This space is connected with the evaporated refrigerant line 158 which refrigerant returns to 75

the unit 154. The unit 154 is controlled by a bulb 159 similar to the unit 104.

Means for humidifying the air in compartment 151 may be provided. Thus the plate or air cooling section 153 is provided with troughs 160 placed on both sides of the plate. A drinking water tank 161 is provided in the upper part of the compartment 151. This tank may be provided with faucet 162 for drinking purposes. It 10 may also be provided with a drip faucet 163 which is adjusted to permit a slow trickle of water into the trough 160 (or it may be periodically opened and closed to provide the desired moisture). Water flows down the troughs 160 along one side 15 of the plate 153 and then by the bent portion 160a to the other side of the plate 153 and eventually, through the pipe 164 to the sump 165. This sump is provided with a purifier 166, made of activated charcoal or the like and submerged 20 therein. Means may be provided for circulating water from the sump 166 to the troughs 160. Thus a pump 167, driven by motor 168 has its suction 169 placed in the sump 165 and its discharge leads through the pipe 170 to the upper 25 trough 160. An overflow pipe 171 permits excess moisture to flow to a moisture evaporator 172 similar to the evaporator 41.

In the modification shown in Fig. 6 a cabinet 200 is provided with a food storage compartment 201 provided with food shelves, not shown. A cooling unit 202 is placed in the upper part of the compartment 201. A refrigerant liquefying unit 203, similar to the unit 104 furnishes liquid refrigerant through the line 204 to the expansion 35 valve 205. Expanded refrigerant flows through a hollow U-shaped sheet metal structure 206 around the ice freezing shelves 207 and from thence through the pipe 208 to the outer hollow sheet metal structure 209. The evaporated refrigerant returns through line 210 to the unit 203.

Means are provided for moistening the air in the compartment 201. To this end, the bottom wall 211 of the compartment 201 may be provided with means for maintaining a body of water, which means may take the form of troughs 212 which are fed by the pipe 213 from the drain pan 214. As moisture condenses on the unit 202 it drips to the drain pan 214, flows through the purifier 215, made of activated charcoal or the like, and from thence flows through the pipe 213 to the troughs 212 where a body of water is maintained in them and from which moisture is picked up by the circulating air. Any excess moisture flows through the overflow pipe 216 55 to the moisture evaporator 217, similar to the evaporator 41. The pipe 216 extends above the bottom of troughs 212 and maintains a body of water in them.

The unit 203 is controlled by a thermostatic bulb 218 in a manner similar to unit 104.

The operation of the various modifications is obvious, being in general similar to that of the modifications shown in Figs. 1 and 2.

While the form of embodiment of the invention as herein disclosed, constitutes a preferred form, it is to be understood that other forms might be adopted, all coming within the scope of the claims which follow.

What is claimed is as follows:

1. Refrigerating apparatus comprising a cabinet having a food storage compartment, a cooling unit for said compartment, a drain pan receiving condensate from said cooling unit, means to purify said condensate, and means to evaporate the purified condensate into the air in said compartment.

ment by convection air currents, said last named means including a surface adapted to be moistened by capillary action.

2. Refrigerating apparatus comprising a cabinet having a food storage compartment, a cooling unit for said compartment, a drain pan receiving condensate from said cooling unit, means to purify said condensate, and means to evaporate the purified condensate into the air in said compartment by convection air currents, said last named means including a porous wall in said drain pan.

3. Refrigerating apparatus comprising a cabinet having a food storage compartment with a vertical door in the front, a cooling unit at the upper part of said compartment, a flat baffle extending horizontally beneath said cooling unit and forming a vertical flat flue at the rear of said compartment, an air moistener behind said baffle, a drain pan beneath said baffle, a pump connected to said drain pan and moistener in fluid circuit relationship, and a purifier in said circuit.

4. Refrigerating apparatus comprising a cabinet having a food storage compartment with a vertical door in the front, a cooling unit at the upper part of said compartment, a flat baffle extending horizontally beneath said cooling unit and forming a vertical flat flue at the rear of said compartment, an air moistener behind said baffle, a drain pan beneath said baffle, a pump connected to said drain pan and moistener in fluid circuit relationship, a moisture evaporator outside said compartment, and an overflow connection between said moisture evaporator and said drain pan.

5. Refrigerating apparatus comprising means forming a food storage compartment including a bottom wall, a cooling unit for said compartment, means for maintaining a body of water on said bottom wall in contact with the air in said compartment, said last named means including a drain pan for said cooling unit, and a flow connection from said pan to said bottom wall.

6. Refrigerating apparatus comprising means forming a food storage compartment including a bottom wall, a cooling unit for said compartment, means for maintaining a body of water on said bottom wall in contact with the air in said compartment, said last named means including a drain pan for said cooling unit, a flow connection from said pan to said bottom wall, and a purifier for the moisture gathered in said pan.

7. Refrigerating apparatus comprising means forming a food storage compartment including a bottom wall, a cooling unit for said compartment, means for maintaining a body of water on said bottom wall in contact with the air in said compartment, a moisture evaporator outside said storage compartment and an overflow from said bottom wall to said evaporator.

8. Refrigerating apparatus comprising a cabinet having a food storage compartment and a freezing compartment, cooling means for said compartments, means for moistening the air in said food storage compartment, a sump for accumulating moisture removed from the air, a fluid flow connection between said means for moistening the air and said sump, and a fluid purifier in contact with said moisture.

9. A refrigerating apparatus comprising a cabinet having a food compartment, a cooling unit for said compartment, a trough above the bottom of said compartment in contact with the air in said compartment, a sump in said compartment receiving moisture separated from the air in said compartment, and fluid flow connection between

- said trough and sump, and a moisture purifier in said cabinet.
10. Refrigerating apparatus comprising a cabinet having a food compartment, a cooling unit for said compartment, a trough above the bottom of said compartment in contact with the air in said compartment, a sump in said compartment receiving moisture separated from the air in said compartment, and a pump for pumping water from said sump to said trough.
11. Refrigerating apparatus comprising a cabinet having a food compartment, a cooling unit for said compartment, a trough above the bottom of said compartment in contact with the air in said compartment, a sump in said compartment receiving moisture separated from the air in said compartment, a pump for pumping water from said sump to said trough and a water purifier.
12. Refrigerating apparatus comprising a cabinet having a food compartment, a cooling unit for said compartment, a trough above the bottom of said compartment in contact with the air in said compartment, a sump in said compartment receiving moisture separated from the air in said compartment, a pump for pumping water from said sump to said trough, and a moisture evaporator outside said compartment adapted to receive excess moisture from said compartment.
13. Refrigerating apparatus comprising a cabinet having a food compartment, a cooling unit for said compartment, a trough above the bottom of said compartment in contact with the air in said compartment, a sump in said compartment receiving moisture separated from the air in said compartment, a pump for pumping water from said sump to said trough and a water purifier in said sump.
14. A refrigerating apparatus comprising in combination, a cabinet having a plurality of walls forming a food storage compartment therein, a cooling element within said food compartment, said cooling element being adapted to condense moisture from the air in said compartment thereon and to have water dripping therefrom, a drain pan for receiving the condensate water dripping from said cooling element, means for removing impurities from said condensate water, and means for causing the purified condensate water to evaporate into the air in said compartment by convection air currents.
15. A refrigerating apparatus comprising in combination, a cabinet having a plurality of walls forming a food storage compartment therein, a cooling element within said food compartment, said cooling element being adapted to condense moisture from the air in said compartment thereon and to have water dripping therefrom, a drain pan for receiving the condensate water dripping from said cooling element, means associated with said drain pan and forming a reservoir therein for maintaining a predetermined quantity of the condensate water in the pan, means for removing impurities from said condensate water, and means for causing the purified condensate water to evaporate into the air in said compartment by convection air currents.
16. A refrigerating apparatus comprising in combination, a cabinet having walls forming a food storage compartment therein, a cooling element in heat exchange relation with air in said compartment for creating a circulation thereof in the compartment, means to circulate water in contact with the air in said compartment, and means for removing impurities from the water being circulated.
17. A refrigerating apparatus comprising in combination, a cabinet having walls forming a food storage compartment therein, a cooling element in heat exchange relation with air in said compartment for creating a circulation thereof in the compartment, means to circulate water in contact with the air in said compartment, means for removing impurities from the water being circulated, and means for evaporating excess water flowing from the compartment to atmosphere outside said compartment.
18. A refrigerating apparatus comprising in combination, a cabinet having walls forming a food storage compartment therein, a cooling element in heat exchange relation with air in said compartment for creating a circulation thereof in the compartment, means to circulate water in contact with the air in said compartment, means for removing impurities from the water being circulated, and means for evaporating excess water flowing from the compartment to atmosphere outside said compartment, said last named means being normally ineffective and rendered effective automatically by the flow of water from the compartment thereto.
19. A refrigerating apparatus comprising in combination, a cabinet having walls forming a food storage compartment therein, a cooling element within said compartment for creating circulation of air therein, said cooling element being adapted to condense moisture thereon and to have water dripping therefrom whereby the circulating air is dehumidified, means for collecting the drip water flowing from said cooling element, means for removing impurities from the water in said collecting means, and means for circulating the purified drip water from said collecting means into contact with the circulating air in said compartment to rehumidify the air.
20. A refrigerating apparatus comprising in combination, a cabinet having walls forming a food storage compartment therein, a cooling element within said compartment for creating circulation of air therein, said cooling element being adapted to condense moisture thereon and to have water dripping therefrom whereby the circulating air is dehumidified, means for collecting the drip water flowing from said cooling element, means for removing impurities from the water in said collecting means, and means for circulating the purified drip water from said collecting means into contact with the circulating air in said compartment to rehumidify the air.
21. A refrigerating apparatus comprising in combination, a cabinet having walls forming a food storage compartment therein, a cooling element within said compartment for creating circulation of air therein, said cooling element being adapted to condense moisture thereon and to have water dripping therefrom whereby the circulating air is dehumidified, means for collecting the drip water flowing from said cooling element, means for removing impurities from the water in said collecting means, means for circulating the purified drip water from said collecting means into contact with the circulating air in said compartment to rehumidify the air, and means for causing evaporation of excess water exteriorly of said compartment.
22. The method of treating air within a re-

frigerator cabinet which consists in, refrigerating the air to withdraw moisture therefrom to thereby dehumidify same, collecting the water dripping from the air refrigerating means, removing impurities from the water in said collecting means, and then circulating the purified drip water into contact with the air in the refrigerator cabinet to rehumidify same.

23. The method of treating air within a refrigerator cabinet which consists in, refrigerating the air to withdraw moisture therefrom to thereby dehumidify same, removing impurities from the moisture extracted from the air, and then circulating the purified moisture into contact with the air in the refrigerator cabinet to rehumidify same.

24. The method of treating air within a refrigerator cabinet which consists in, refrigerating the air to withdraw moisture therefrom to thereby dehumidify same, collecting the water dripping from the air refrigerating means, removing impurities from the water in said collecting means, and then circulating the purified drip water into contact with the air in the re-

frigerator cabinet to rehumidify same while evaporating excess water dripping from the air refrigerating means to atmosphere outside of the refrigerator cabinet.

25. The method of conditioning air within an enclosure which consists in, treating the air to withdraw moisture therefrom to thereby dehumidify same, collecting water from the air treating means and removing impurities therefrom, and then exposing the purified water to air within the enclosure to evaporate a portion thereof into the air to rehumidify same.

26. The method of conditioning air within an enclosure which consists in, treating the air to withdraw moisture therefrom to thereby dehumidify same, collecting water from the air treating means and removing impurities therefrom, exposing the purified water to air within the enclosure to evaporate a portion thereof into the air to rehumidify same, and evaporating excess water to atmosphere outside of the enclosure.

HARRY B. HULL.
